LUBRICATING DEVICE FOR ELECTRIC SWITCHES

Ernst Schimann, Berlin-Spandau, Germany, assignor to Fides Gesellschaft für die Verwaltung und Verwertung von gewerblichen Schutzrechten m. b. H., Berlin, Germany

Application January 28, 1939, Serial No. 253,264
In Germany February 16, 1938

3 Claims. (Cl. 200—166)

For the continuous supply of oil to the contact points of electrical switches it has already been proposed to provide oil storage devices which supply oil to the contact points. This is 5 performed in such a manner that the oil storage device is associated with the fixed contacts in that a rotatable roller or the like is provided on the wiper support which is carried round on the rotary movement and thereby slides over the 10 fixed contact.

The invention relates to an oil supply device for oiling the movable contacts of wipers, preferably of wipers of selectors in telephone installations and consists in providing the wiper with 15 an oil storage device supplying an oil film to the contact points. As an oil storage device a layer of material soaked in oil is used, e. g., a porous material, which is situated in an opening in the spring portion of the contact arm and 20 conducts the oil owing to capillary effect as well as by the centrifugal force due to the movement of the arm, so that the contact points are easily supplied with oil so as to form an oil film.

The invention is described with reference to 25 an embodiment which represents a wiper with two contact springs on an enlarged scale, of which the upper spring is removed in order to show the extending piece with the oil storage device in between the two springs.

30 The separating piece 1 for the two springs 2 is provided with an opening 3 which serves to hold the oil storage device of felt or the like which projects like a wick from one front part 4. The felt is soaked in oil which passes over the wick 35 4 in the neighborhood of the contact points 6 of the wiper and covers these with a thin layer of oil, the effect being increased by the centrifugal force occurring on displacement of the wiper.

40 Thus a continual automatic supply of oil to the contact points of the wiper is produced. The

renewing of the porous material is easily performed in this construction by lifting up one of the springs 2. For the purpose of more convenient replacement of the oil the storage device can be so arranged that the felt or the like 5 projects sideways out of the spring. Also the oil storage device can be arranged on the contact springs themselves by corresponding arrangement of the wiper.

What is claimed is:

1. A wiper assembly for an electrical switch, comprising two similarly shaped wiper blades each having a shank portion and, at or near its outer extremity, a contact portion, means including a substantially flat spacing member between the shank portions of said two blades for clamping said blades in a superimposed but spaced apart relationship, said spacing member having a slot opening toward the contact portions of said blades, and a pad of oil soaked material in said slot and in contact with the inner surfaces of both of said blades. 10

2. A rotary wiper assembly as claimed in claim 1, wherein said slot is so configured that its walls converge toward the contact portions of said 15 blades, and wherein said pad is substantially wedge shaped to dovetail with the convergent walls of said slot thereby to prevent movement of the pad in the slot toward the contact portions of the blades. 20

3. An electrical contact, including a substantially flat member having a slot opening upon and extending inwardly from one edge, two metallic members each having a flat portion and a contiguous contact portion, and means for fastening said last two members to the opposite sides of said first member with their flat portions covering the sides of said slot to form a well and with their contact portions extending slightly beyond the opening of said well. 30
